Des. 214,447
Patented June 17, 1969

214,447

FLASH WELDER

Arthur L. Williams, Warren, Ohio, assignor to The McKay
Machine Company, Youngstown, Ohio

Filed May 21, 1968, Ser. No. 12,026

Term of patent 14 years

Int. Cl. D15—05

U.S. Cl. D26—1

FIG. 2.

FIGURE 1 is a front elevational view of a flash welder, showing my new design,

FIGURE 2 is a top plan view of the welder, and

FIGURES 3 and 4 are left and right end views, respectively, of the welder.

I claim:

The ornamental design for a flash welder, substantially as shown.
